ARTIFICIAL BAIT

James E. Lavitt, Everett, Wash., assignor to J.
Bruce Watson, Everett, Wash.

Application August 7, 1934, Serial No. 738,853

3 Claims. (Cl. 43—45)

The present invention relates to new and useful improvements in artificial baits and has for its primary object to provide, in a manner as hereinafter set forth, a device of this character which will be highly attractive to the fish.

Other objects of the invention are to provide an artificial bait which will be comparatively simple in construction, strong, durable, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in side elevation of an artificial bait constructed in accordance with the present invention.

Figure 2 is a longitudinal sectional view, taken substantially on the line 2—2 of Figure 1.

Figure 3 is a detail view in side elevation of the inner spoon.

Referring now to the drawing in detail, it will be seen that the embodiment of the present invention which has been illustrated comprises an outer spoon 1 of any suitable flat material, preferably a highly polished substantially flat metal. The spoon 1 includes oppositely curved tail fins 2 which, as will be understood, cause said spoon to rotate as it is drawn through the water. Projecting from the rear end of the outer spoon 1, between the tail fins 2, is an apertured extension 3 to which a hook 4 is loosely connected through the medium of a ring 5.

The forward end or nose portion of the outer spoon 1 has loosely connected thereto a ring 6 which, in turn, is loosely connected to a swivel 7. The swivel 7 is adapted for connection with a line (not shown).

The outer spoon 1 has formed therein a longitudinally elongated opening 8 in which an inner spoon 9 is rotatably mounted. The inner spoon 9 may also be of any suitable flat material, preferably a substantially flat, highly polished metal. If desired, the spoons 1 and 9 may be of metals of contrasting colors, for example, brass and nickel. The inner spoon 9 includes integral, oppositely curved tail fins 10 for causing said inner spoon to rotate as the artificial bait is drawn through the water. The tail fins 10 of the inner spoon 9 are preferably curved oppositely to the corresponding fins 2 of the outer spoon 1 for causing the spoons to rotate in opposite directions.

It will be noted that the opening 8 in the outer

spoon 1 conforms substantially to the longitudinal outline of the inner spoon 9.

The outer spoon 1 has formed integrally therewith an integral apertured ear 11 (see Figure 2) which projects into the opening 8 between the fins 10 of the inner spoon 9, said ear constituting a bearing for the trunnion 12 which projects longitudinally from the rear end of said inner spoon 9 between said fins 10. It will be noted that the ear 11 is curved outwardly and then inwardly 10 at right angles to the inner spoon 9. A thrust bearing 13, preferably in the form of a colored bead, is mounted on the trunnion 12 between the inner spoon 9 and the ear or bearing 11.

Mounted on the forward end portion of the outer spoon 1 and extending substantially transversely into the forward end portion of the opening 8 is a bearing 14 in which a trunnion 15 which projects longitudinally from the forward end of the inner spoon 9 is journaled. It will thus be seen that the inner spoon 9 is mounted to rotate freely in the outer spoon 1. The inner spoon 9 has formed therein a plurality of indentations 16 which enhance the reflecting or flashing qualities of said spoon and improve the action thereof.

It is thought that the operation of the device will be readily apparent. As the artificial bait is drawn through the water, the outer spoon 1 rotates on the swivel 7 and the inner spoon 9 rotates in the opposite direction in the bearings 7 and 14.

It is believed that the many advantages of an artificial bait constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

1. An artificial bait of the class described comprising an outer spoon having an opening therein, bearings on the outer spoon extending transversely into the opening, an inner spoon rotatably mounted in the opening, trunnions on the inner spoon journaled in the bearings, and means for rotating the outer and inner spoons as the bait is drawn through the water.

2. An artificial bait of the class described comprising an outer spoon having an opening therein, bearings on said outer spoon extending substantially transversely into the opening, an in-

ner spoon rotatably mounted in the opening, trunnions on the inner spoon journaled in the bearings, said inner spoon having indentations therein, curved fins on the rear end portion of the outer spoon for rotating said outer spoon in one direction as the bait is drawn through the water, and curved fins on the rear end portion of the inner spoon for rotating said inner spoon in the opposite direction as the bait is drawn through the water.

3. An artificial bait of the class described comprising an outer spoon formed with a substantial-

ly flat body portion and having an opening therein, said outer spoon being formed with oppositely curved fins on one end thereof, and an inner spoon rotatable in the opening in the outer spoon, the body portion of the inner spoon being substantially flat and formed with oppositely curved fins on one end thereof, the curvature of the fins on the inner and outer spoons being such as to cause the outer spoon to rotate in the opposite direction to that of the inner spoon.
